United States Patent Office

Des. 197,151
Patented Dec. 17, 1963

197,151

COMBINED JAR AND CLOSURE THEREFOR

Edward H. Lawton, Toledo, Ohio, assignor to Owens-Illinois Glass Company, Toledo, Ohio, a corporation of Ohio

Filed Nov. 13, 1962, Ser. No. 72,474

Term of patent 14 years

(Cl. D58—25)

The FIGURE is a perspective view of a combined jar and closure therefor showing my new design.

The surface decorations illustrated are repeated on the opposite side of the combined jar and closure therefor.

I claim:

The ornamental design for a combined jar and closure therefor, substantially as shown and described.
